HOLDER FOR PAPER MATCHES

Robert C. Read, New York, N. Y.

Application October 1, 1937, Serial No. 166,760

13 Claims. (Cl. 206—31)

My invention relates to holders for packages of paper matches of the well-known form in which a body of matches is secured in a closure provided with a striking flap and a front flap.

One object accomplished by my invention is the provision of a holder for matches of the type described, in which the match package is held securely in position with the striking flap exposed and the body of matches also exposed, so that a single match can be removed from the package and struck on the flap provided for that purpose with the use of but one hand.

Another object attained by my invention is the provision of a holder constructed of comparatively few parts so arranged as to permit easy and rapid insertion and removal of the match package from the holder.

Another object accomplished by my invention is the provision of a holder of the type described in which the parts are simple and cheap in construction and durable in use.

Still another object attained by my invention is the provision of a match package holder so shaped as to minimize the possibility of igniting the matches from lighted smoking materials accidentally placed on the match package or on the holder.

Other features and objects of my invention will appear more fully from the following description.

I shall describe one form of holder embodying my invention, and shall then point out the novel features thereof in claims.

In the accompanying drawing, Fig. 1 is a perspective view of one form of holder embodying my invention. Fig. 2 is a perspective view illustrating a portion of the device shown in Fig. 1. Figs. 3 and 4 are detailed views of the device shown in Fig. 1, and Fig. 5 is a perspective view of the clip C forming a part of the holder illustrated in the preceding figures and also embodying my invention.

Similar reference characters refer to similar parts in each of the several views.

Referring first to Fig. 1, the reference character A designates a base which may be of any suitable material and of any reasonable size, but should preferably be of sufficient mass to maintain its position while a match is being struck against it. In the form here shown, the base A is formed integrally with an ash tray B, the base forming a portion of the rim of the tray, but this particular construction is not essential. The base A may be formed on, or attached to, a support of any desired kind.

The base A, as best seen in Figs. 2, 3 and 4, is provided with a body portion 1, having a substantially flat top face inclined downwardly and provided with a recess 2 defined by the edges 4 of the body portion 1 of the base. This recess 2 as best seen in Fig. 3, has an inclined bottom, so that the depth of the recess diminishes as it approaches the top of the body portion 1. The recess 2 is deep enough at its lower end to receive a package D of paper matches of the usual and well known form. The usual paper closure flap of the match package may be torn off or may be folded under the body of matches, so that the matches themselves are exposed, as shown in Fig. 1.

After a package of matches has been inserted in the recess of the base, a clip C is attached to the base to clamp the matches in the recess. The clamp C, as shown in Figs. 1 and 4 and illustrated in detail in Fig. 5, comprises a body portion 8 containing an aperture and two side portions 9 and 10. The clip may be formed of any suitable resilient material, such for example, as brass or steel, and is formed at its ends with resilient ears 13 and 14 which embrace rounded ribs 5 and 6 on the base A. With this construction the resilient ears on the clip C clamp the clip firmly in place on the base by their engagement with the ribs on the base. A shoulder 7 formed on the base A enters a notch 14 in the ear 12, thereby assisting in the proper location of the clip when it is applied to the base and preventing transverse movement of the clip with respect to the base.

The rim of the body portion of the clip is struck downwardly at points 11 near the end of each side of the aperture to provide fingers which press directly upon the striking flap of the match package and hold the parts firmly in place.

It will be seen that the rim of the clip overlies the edges of the paper closure of the match package, but the aperture in the clip exposes the body of the matches and permits their convenient removal without displacement of any parts of the match holder. For this purpose the aperture in the clip is preferably made somewhat smaller than the recess 2 in the base A.

The clip may be readily removed from the base by insertion of the user's finger into a groove 15 formed in the back of the base A partly underlying the ear 13 of the clip, as best shown in Fig. 2.

By virtue of the inclined face of the match holder, a cigarette or cigar inadvertently placed

upon the match package will, by gravity, roll off of the holder, and, in the modification here shown, into the ash tray. With this construction there is little probability that the entire package 5 of matches can be ignited by accidental contact with lighted smoking materials carelessly placed on the match package or the holder.

Another advantage of the holder embodying 10 my invention, is that due to the shape of the recess 2 into which the match package is inserted, the end of the package provided with the striking flap is securely held by the fingers 11 of the clip in a position well below the top of the holder, thereby facilitating the use of the striking flap for igniting the match. At the same 15 time the shape of the recess, diminishing in depth toward its top, tends to force the free ends of the matches of the match package upwardly through the recess in the clip, thereby permitting 20 the matches to be grasped easily for removing them from the package.

It will be noted that the surfaces of the clip 25 and the base are smooth and free from projections. These surfaces may be employed to receive advertising matter stamped or printed upon the clip or base, or any other suitable emblem, legend or insignia may be applied to the parts of the holder by any of the well known processes.

It will be understood that while I have 30 illustrated my invention as applied to an ash tray of a particular form, the invention is not limited to this particular embodiment, but the holder is equally applicable to a construction in which the base takes any suitable form or is attached to or 35 formed in a receptacle of any kind.

It will also be understood that while I have 40 shown the holder designed to receive a package of paper matches of the conventional and well-known type, the holder may be modified in its design to receive match packages of any size or shape, and that the parts of the holder may be 45 constructed of any suitable material and may be provided with ornamentation or accessories to any appropriate degree.

Although I have herein shown and described 50 only one form of match holder embodying my invention, it is understood that various changes and modifications may be made therein within the scope of the appended claims without departing 55 from the spirit and scope of my invention.

Having thus described my invention, what I 60 claim is:

1. A holder for use in connection with a package of matches and comprising a base, a separate 55 clip for clamping the package of matches against the base and provided with an aperture through which the matches may be removed from the package, and cooperating means on the base and the clip for removably retaining the clip in 60 clamping position.

2. A holder for use in connection with a package of matches and comprising a base having a recess to receive the package of matches, and a clip attached to said base for retaining the package in said recess and provided with a rim for 65 engaging said package and an aperture for exposing the matches.

3. A holder for use in connection with a package of matches and comprising a base, a separate 70 clip for clamping the package of matches against the base, said clip having spaced ears for receiving said base to limit movement of said clip vertically and longitudinally of the clip, and said base having a shoulder entering a notch in the clip to limit transverse movement of the clip.

4. A holder for use in connection with paper match packages consisting of a body of matches enveloped in a wrapper including a striking flap and a closure flap, said holder comprising a base to receive the match package with the closure flap folded behind the body of matches, a clip separately attached to said base and provided with an aperture having a rim for engagement with said closure flap while exposing said body of matches, and fingers on said clip engaging opposite ends of the striking flap. 10

5. A holder for use in connection with paper match packages consisting of a body of matches enveloped in a wrapper including a striking flap and a closure flap, said holder comprising a base 15 having a recess to receive the match package with the closure flap folded behind the body of matches, said recess being deep enough at one end to allow the striking flap to lie substantially level with the face of the base and so shallow at 20 the opposite end that the body of matches is held above the level of the face of the base, and a clip separately attached to the base and provided with integral means for engaging the ends of the striking flap and with an aperture to 25 expose the body of matches.

6. A holder for use in connection with a package of matches and comprising a base provided with a substantially rectangular recess and parallel ribs adjacent the short sides of such recess, a 30 clip having ears to receive said ribs and provided with an aperture registering with but smaller than said recess to form a rim overlying the edges of said recess, and fingers integral with said clip and depending into said recess for clamping a 35 package of matches in said recess.

7. A holder for use in connection with a package of matches and comprising a base having spaced parallel ribs and a shoulder, and a clip 40 having ears to engage said ribs and shoulder whereby the clip is secured to said base to clamp a package of matches against the base.

8. A holder for use in connection with a package of matches and comprising a base having a flat upper face inclined with the horizontal and 45 provided with a recess the depth of which diminishes gradually toward the upper end of the base, and a clip with resilient ears engaging the base and provided with integral means for clamping against the base a package of matches inserted in said recess with the match heads adjacent the upper end of the base whereby objects laid on the holder will roll away from the heads of the matches. 50

9. An ash tray comprising a bowl having a 55 rim shaped to form a base with a top surface inclined downwardly into the bowl and a clip removably secured to said base to clamp a package of matches between the base and clip, said clip being provided with an aperture through 60 which the matches may be singly removed from the package.

10. A holder for use in connection with a package of matches and comprising a base having a top terminating in curved ribs overhanging opposite ends of the base and a resilient clip having an apertured body portion covering said top and curved ears to receive said ribs to clamp a package of matches between the top of the base and the body portion of said clip, and a groove in 70 said base located in part under the edge of one ear on said clip to receive a finger for removing the clip from the block.

11. A clip for clamping a package of matches to a base and comprising an integral piece of re- 75

- silient material having a substantially flat body portion provided with an aperture to permit removal of matches from the package, and a pair of downwardly curved integral ears formed on opposite ends of the clip to receive the base one ear being formed with a notch to receive a shoulder on the base, the rim of said body portion being inclined downwardly at one end of each side of said aperture to form fingers to engage the package of matches.
- 5 12. A holder for use in connection with a package of matches and comprising a base provided with ribs, and a separate clip for clamping the package of matches against the base and having

a body portion to engage a part of said package and a pair of ears for engaging said ribs on opposite sides of said package to retain the clip in clamping position.

13. A holder for use in connection with a package of matches and comprising a base and a separate clip provided with an aperture smaller than said package, and cooperating means on the base and clip for removably retaining the clip in position, said base and clip being formed to define a recess to completely enclose the match package except for the aperture in said clip, whereby the package is retained in the holder.
